UNITED STATES PATENT OFFICE.

RODNEY G. CHASE, OF ELSDON, ILLINOIS.

FASTENING FOR REFRIGERATOR-DOORS.

SPECIFICATION forming part of Letters Patent No. 516,296, dated March 13, 1894.

Application filed December 8, 1892. Serial No. 454,429. (No model.)

To all whom it may concern:

Be it known that I, RODNEY G. CHASE, a citizen of the United States, residing in Elsdon, in the county of Cook and State of Illinois, have invented certain new and useful Improvements in Fastenings for Refrigerator-Doors, of which the following is a specification, reference being had to the accompanying drawings.

10 My invention is intended to provide a fastening for refrigerator doors which shall by the act of securing it draw the door firmly shut and by its release start the door open, thus dispensing with the necessity of prying 15 or hammering upon the door in order to open and close it. A further purpose is to insure the tight closure of the door notwithstanding slight inaccuracies in the placing or fitting of the fastener. It is intended specially for the 20 doors of refrigerator cars as they are very liable to stick and be difficult of operation, owing to their exposure to the weather, and in consequence of the racking of the cars.

In the accompanying drawings: Figure 1 25 is a side view of a portion of the door and frame to which the fastening is attached. Fig. 2 is a cross section of the same. Fig. 3 is a side view like Fig. 1 except that the fastening is shown in the open or released position instead of its closed position. Fig. 4 30 is a view on a larger scale of the socket which is attached to the door frame.

A is the car door to which is pivoted a hand lever B. Upon each side of the pivotal point 35 C of said hand lever are secured the ends of the locking bars D and E. The outer ends d, e of these bars are bent so as to incline toward the door frame as seen in Fig. 2. Near the outer edge of the door are secured stir- 40 rups F, G through which the bars may slide.

Secured to the door frame above and below are sockets H, I which are provided with recesses (best seen in Figs. 2 and 4) for the reception of the ends of the bars D, E. These 45 recesses are so shaped that when the bar first enters, its bent end comes in contact with the sloping wall h, i at the entrance of the recess, but when the bars are fully projected as shown in Figs. 1 and 2 the straight part of 50 the bar comes in contact with the straight wall h', i' so that there is no tendency to force

back the locking bars by any pressure on the door. The inner walls of the recesses in the sockets H, I have sloping portions h², i² and straight portions h³, i³, upon which the inner 55 side of the locking bars may act when they are withdrawn. The effect is, that when the locking bars are projected, the door is drawn closely shut, and by means of the straight bearing portions is held firmly closed, while 60 upon the withdrawal of the locking bars the bent ends act upon the sloping inner walls of the recesses h², i² and force the door partially open, so that it is relieved from pressure and can be easily opened by hand. The 65 straight bearing on the locking bars when fully projected, insures the perfect closure of the door notwithstanding small variations in the length of the bars or corresponding variations in the placing of the sockets, for a 70 slight variation in this respect does not affect the amount of draw on the door produced by the beveled end of the bars. Thus a difficulty experienced with the use of locking bars having bent ends which fit into inclined sockets 75 is obviated, for it is apparent that in such sockets the slightest difference in the placing of the sockets or the slightest inaccuracy in the length of the bars themselves, results in the corresponding difference in the position 80 of the door. It is obvious, furthermore, that the relative proportions of the inclined and straight bearing walls of the sockets may be considerably varied without altering the operation of the device, in fact the straight portions h³, i³ need be no more than sufficient to afford a proper backing to the inclined faces h², i² which are the operating faces in opening the door. And it is further obvious that 85 the bearing face h, i can be also reduced, it 90 being only necessary that the total amount of draw furnished by the joint action of the inclined faces h and i and the outer surfaces of the bent ends d, e of the locking bars be sufficient to operate the door satisfactorily. It 95 is obvious, furthermore, that only a single locking bar is absolutely necessary, but in almost all instances two locking bars are preferable as a tighter joint can be thereby secured.

100 I claim—

A door-fastening, comprising a socket hav-

ing oppositely disposed inclined and straight surfaces, a locking-bar having at its end oppositely disposed inclined and straight bearing-portions and means for moving the locking-bar into and out of the socket; the inclined and straight bearing-surfaces of the socket serving as bearings for the inclined and straight bearing-portions of the locking-bar, whereby one set of inclined and straight bearing portions are brought successively

into action during the protraction of the locking-bar, and the opposite set of inclined and straight bearing-portions are brought successively into action during the retraction of said bar, substantially as set forth.

RODNEY G. CHASE.
